(57) **CLAIM**

We claim the ornamental design for a display screen or portion thereof with graphical user interface, as shown and described.

DESCRIPTION

FIG. 1 is a front view of a first embodiment of a display screen or portion thereof with graphical user interface showing our new design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof;

FIG. 6 is a front view of a sixth embodiment thereof;

FIG. 7 is a front view of a seventh embodiment thereof;

FIG. 8 is a front view of an eighth embodiment thereof;

FIG. 9 is a front view of a ninth embodiment thereof;

FIG. 10 is a front view of a tenth embodiment thereof;

FIG. 11 is a front view of an eleventh embodiment thereof;

FIG. 12 is a front view of a twelfth embodiment thereof;

FIG. 13 is a front view of a thirteenth embodiment thereof;

FIG. 14 is a front view of a fourteenth embodiment thereof;

FIG. 15 is a front view of a fifteenth embodiment thereof;

FIG. 16 is a front view of a sixteenth embodiment thereof;

FIG. 17 is a front view of a seventeenth embodiment thereof;

FIG. 18 is a front view of an eighteenth embodiment thereof;

FIG. 19 is a front view of a nineteenth embodiment thereof;

FIG. 20 is a front view of a twentieth embodiment thereof;

FIG. 21 is a front view of a twenty-first embodiment thereof;

FIG. 22 is a front view of a twenty-second embodiment thereof;

FIG. 23 is a front view of a twenty-third embodiment thereof;

FIG. 24 is a front view of a twenty-fourth embodiment thereof;

FIG. 25 is a front view of a twenty-fifth embodiment thereof;

FIG. 26 is a front view of a twenty-sixth embodiment thereof;

FIG. 27 is a front view of a twenty-seventh embodiment thereof;

(Continued)

FIG. 28 is a front view of a twenty-eighth embodiment thereof;

FIG. 29 is a front view of a twenty-nineth embodiment thereof;

FIG. 30 is a front view of a thirtieth embodiment thereof;

FIG. 31 is a front view of a thirty-first embodiment thereof; and,

FIG. 32 is a front view of a thirty-second embodiment thereof.

The outer perimeter broken lines in the drawings represent a display screen or portion thereof and form no part of the claimed design. The remaining broken lines in the drawings illustrate portions of the graphical user interface that form no part of the claimed design.
